UNITED STATES PATENT OFFICE.

EDWIN S. MIX AND JOHN RALPH WHITEHOUSE, OF ROCHESTER, NEW YORK, AS
SIGNORS TO HICKOK MANUFACTURING COMPANY, INC., OF ROCHESTER, NEW YORK,
A CORPORATION OF NEW YORK.

COMPOSITE-STRIP-FORMING MACHINE.

Application filed August 2, 1926. Serial No. 126,636.

The present invention relates to a composite strip forming machine and an object of the invention is to provide a strip forming machine which will fold the edges of a sheet 5 of material about a filler or body and adhesively secure said sheet of material to the body in an effective manner. A further object of the invention is to provide a strip forming machine which will unite two pieces 10 of material and will thereafter act on the strip in such a manner as to obtain a positive adhesion between the materials entering into the strip.

To these and other ends, the invention 15 consists of certain parts and combinations of parts, all of which will be hereinafter described: the novel features being pointed out in the appended claims.

In the drawings:

20 Fig. 1 is a plan view of the machine constructed in accordance with this invention;

Fig. 2 is a sectional view of the machine on the line 2—2, Fig. 1;

Fig. 3 is a front view of the machine;

25 Fig. 4 is a section on the line 4—4, Fig. 3;

Fig. 5 is a vertical section through the machine on the line 5—5, Fig. 1;

30 Fig. 6 is a vertical section through the machine associated with means for applying an adhesive to the core or center piece entering into the strip;

Fig. 7 is a plan view of the adhesive applying mechanism;

35 Fig. 8 is an enlarged fragmentary view showing the manner of operating the clutch and the brake;

Fig. 9 is a perspective view of the folder; and

40 Fig. 10 is a transverse section through the folder.

The present invention is particularly designed for making strips from which belt loops may be formed, but it is apparent that the invention is capable of being used 45 for forming composite strips used in other arts. In the illustrated embodiment of the invention, 1 indicates a roll from which a fabric 2 is drawn, this fabric serving as a core or body of the completed strip as illustrated in Fig. 10 of the drawings. This strip 2 is first coated with a suitable adhesive. In this instance, the adhesive is a glue contained in a pot 3 surrounded by a

hot water chamber 4 heated in any suitable manner as by an electrical heater introduced into a hollow transverse rib 5 formed in the bottom of the hot water pot or receptacle and opening laterally for the introduction of the heater. From the roll 1 the tape or fabric 2 passes over a roller 6 supported to one side of the glue pot 3. The tape then passes downwardly under a roller 7 which is suspended from a cross bar 8 secured from thumb nuts 9 each across the pot 3, the roller 7 being submerged in 60 the glue of the glue pot. From the roller 7 the tape passes upwardly to a squalgee embodying rollers 10 and 11, the latter being supported on a swinging frame 12 which is acted on by a spring 13 to hold the roller 70 10 with yielding pressure to the roller 11. After the fabric passes from the squalgee, it passes over a guide roller 14 to the guide 75 15 of the forming machine. The width of this guide is greater than the width of the fabric 2, so that a strip 16 of leather or other suitable material of greater width than the fabric may pass through the guide simultaneously with the fabric. Both strips of material 2 and 16 then pass together to 80 a folder which consists of two curved walls 17 projecting upwardly on opposite sides of the bottom 18 of the folder and gradually converging toward the end of the folder. Depending from the top of the folder is a 85 fin 19 secured to one of the guides 17 and positioned in spaced relation to the bottom 18 while, at the same time, being centrally arranged with reference to the former. These curved sides turn up those portions 90 of the strip 16, the projection beyond the sides of the fabric 2 and fold such projecting portions over the uppermost surface of the strip 2 in the manner shown in Fig. 10, the fin 19 maintaining the central position of the adjacent edges of the strip 16 with reference to the strip 2 so that there is no tendency for the projecting edges to be improperly laid upon the strip 2.

When the composite strip issues from the 100 folder, shaped in the manner shown in the section, Fig. 10, it is then subjected to a combination pressure and beating mechanism. This combination beating and pressure mechanism embodies, in this instance, 105 two rollers 20 and 21, one arranged above

the other. The roller 20 is grooved at 20^a and is mounted with its axis in a fixed relation to the path of travel of the composite strip. In this instance, this roller is secured 5 to a shaft 22 supported in a housing 23, the shaft also carrying a worm wheel 24 which is enclosed by the housing 23 and meshes with a worm 25 journalled in said housing 23. The shaft of this worm wheel 25 projects from the housing and carries a grooved 10 wheel 26 which has a clutch face 27 on one side thereof.

Mounted with its shaft 28 in alignment with the worm shaft 25 is an electric motor 29. This shaft 28 has a coupling 30 one end through which a shaft 31 is connected thereto. Mounted on the shaft 31 is a clutch member 32, this clutch member being secured by a key 33 to the shaft 31 so that the clutch 20 member turns with the shaft but may move axially thereof, in order to cooperate with the clutch face 27 on the grooved wheel 26 to establish driving connection with the clutch face 27 on the grooved wheel 26 to establish 25 driving connection between the motor 29 and the worm wheel 25. It is apparent that the speed of rotation of the motor shaft 28 is through the worm 25 and the worm wheel 24 reduced so that the speed of rotation of the 30 grooved wheel 20 is materially slower than that of the electric motor shaft.

Movement of the clutch member 32 may be effected in any suitable manner. In this instance, a yoke 34 pivoted at 35 to a fixed part 35 has an adjustable portion 36 thereon engaged by a cam surface 37 on a sliding cam 38 which is guided in ways 39 on the frame of the machine and controlled by an arm 40 on a rod 41 to which a treadle or other suitable 40 operating member may be connected. The depression of the rod 41 against the action of the spring 42 lowers the cam 38 and forces the yoke in a direction to draw the clutch member 32 in engagement with the clutch 45 face 27 to effect the driving of the lower roller 20 which acts on the underside of the form strip and through the latter rotates the upper roller 21.

It is desirable that when the clutch connection 50 between the motor or power element and the roller 20 is broken that the movement of the latter shall be immediately stopped and to this end a brake is employed which cooperates with the walls of the groove in the member 26 to brake the action of the shaft carrying the worm 25. In this instance, this brake is in the form of a bell crank lever 43 pivoted at 44 to a fixed part and having a 55 brake portion 45 for engaging in the groove of the wheel 26. The other arm of the bell crank lever 43 has pivoted thereto at 46 an arm 47 on the rod 41. The depression of the 60 rod 41 swings the bell crank lever 43 to carry the brake lever 45 out of engagement with 65 the brake 46 when the bell crank lever 42 is

moved out of engagement with the clutch face 27. A spring pressed plunger 48 also acts on the bell crank lever 43 in a direction to move the brake portion 45. The spring pressed plunger together with the spring 42 70 act together to produce the elevation of the rod 41, so that when the pressure on the rod is relieved the rod moves upwardly to break connection with the clutch member 23 and the clutch face 27 and also to shift the brake 75 member 45 into engagement with the grooved wheel 26.

The housing 23 is supported on a base 49 which also supports a frame 50 into which the housing 23 projects to position the wheel 80 20 below the wheel 21. This frame 50 has an opening 51 opposite the wheel 20 through which a screw 52 may be reached. This screw secures a washer 53 which holds the wheel 20 to the shaft 22 and permits the 85 ready removal of the wheel 20 for the purpose of cleaning. The opposite sides of the frame 50 above the roller 20 are provided with guides 54 in which bearing guide blocks 55 are arranged, this guide block being connected by a yoke 56 and supporting a shaft 57 which carries the roller 21, the periphery of this roller being formed so as to enter the groove 20^a formed in the roller 20 in order to exert pressure upon the strip passing between the two rollers. This pressure is equal to the weight of the roller 21, bearing blocks 55, the yoke 56 and the parts carried thereby due to the fact that the roller is loosely supported by vertical movement on the guides 54 through said bearing blocks 55. A scraper 70 pivoted at 71 and held toward the roller 21 serves to maintain the latter free from glue.

With the end in view of producing a beating or pounding action on the strip as it 105 passes between the rollers, a beating mechanism is employed comprising, in this instance, two wheels 58 formed with bevelled teeth or projections 59 and secured to the wheel 21 to turn with the latter. For cooperating with these tooth wheels 58, two plungers 60 are provided, connected by a cross piece 61 to a plunger 62 which is guided in a frame 63 supported on the frame 50 preferably by being hinged at 64 to said frame at one side and held at its other side by a thumb screw 65, thus permitting the frame 63 to be swung upwardly to open up the upper ends of the guide slots 54 in order that the bearing blocks 55, connecting yoke 56, the wheel 21 and the toothed wheels 58 may be removed from the machine for the purpose of cleaning. A weight 66 is secured to the slide rod 62 and projects from opposite sides to cooperate with guides 67 formed on the movable frame piece 63. Adjustable plungers 68 depend from the frame 63 above this weight 66 into bores formed in said weight, these bores containing springs 69 which act between the bottoms of the bores and the ends of the plunger 110 115 120 125 130

68 and opposite the upward movement of the weight.

The operation of the invention will be understood from the foregoing, but it may be summarized as follows: A strip of material such as a fabric 2 is passed into a glue pot 3 and passes from the latter to the guide 15 which also receives a strip 16 preferably of leather to be wrapped around the fabric 2. The two strips then pass together from the guide 15 to the folder which turns the projecting edges of the strip 16 over the uppermost surface of the strip 2. The two pieces of material unite as a single strip then pass to the former between the two wheels 20 and 21. The uppermost wheel 21 is moved vertically and is weighted so that the material is subjected to the pressure of the weights imposed on such wheel. In addition to being weighted, this wheel is without moving it out of contact with the work, subject to successive impacts or pulsations which produce a beating action upon the strip as the latter passes between the two rollers 20 and 21. This beating action is obtained by the two toothed wheels 58 being engaged by the two plungers 60 which are acted upon by the weight 66 and the springs 69. This weight and springs are imposed upon the roller 21. It is found that this beating is desirable in order to obtain a positive adhesion between the pieces of material entering into the formation of the completed strip. After being subjected to the beating action, the strip issues from the machine and when the adhesive is completely dried, the strip may be cut up into small pieces to form loops from belts.

What we claim as our invention and desire to secure by Letters Patent is:

1. A composite strip forming machine comprising means for applying an adhesive to one of the materials entering into the strip, a folding device through which the strip forming materials are passed to fold the opposite edges of one of the strip materials about the body forming portion of the strip, and a beating mechanism operating on the strip as it passes from the folding device said beating mechanism having a portion held with pressure in contact with the work.

2. A composite strip forming machine comprising means for applying an adhesive to one of the materials entering into the strip, a folding device through which the strip forming materials are passed to fold the opposite edges of one of the strip materials about the body forming portion of the strip, and a beating mechanism operating on the strip as it passes from the folding device, said beating mechanism embodying a pair of rollers through which the strip passes, one of said rollers being held with pressure against the work and means

for imparting a pulsating action to one of said rollers without moving said roller out of contact with the strip.

3. A composite strip forming machine comprising a beating mechanism embodying a pair of rollers between which the strip is passed, and means for imparting a pulsating movement to the roller without moving said roller out of contact with the strip. 75

4. A machine for forming strips embodying a beating mechanism comprising two rollers between which the strip passes, one of said rollers being held toward and the other being movable away from the same, a toothed member turning with said last mentioned roller, and a plunger yieldingly held in engagement with said toothed member. 80

5. A strip forming machine embodying a pair of rollers through which the strip is passed, one of said rollers being movable toward and from the other, two toothed members being arranged on opposite sides of the movable rollers and turning therewith, and yielding means cooperating with said toothed members and constructed to apply pressure to said roller to hold it toward the first mentioned roller. 85

6. A strip forming machine embodying a beating mechanism comprising two rollers, one of which is movable toward and from the other, and means for imparting a pulsating movement to said last mentioned roller, said means comprising a toothed member and a yielding pressure device 100 cooperating with the toothed member to hold the last mentioned roller toward the other roller. 95

7. A composite strip forming machine comprising means for adhesively uniting two strips, and a combined pressure and beating mechanism having a portion held with pressure in constant contact with the composite strip after its component parts are united and before the adhesive is dry. 105

8. A combined pressure and beating mechanism for uniting material comprising two rollers between which the material passes, one of said rollers being held with pressure in contact with the material and mechanism for imparting pulsations to said roller without moving it out of contact with the material. 110

9. A combined pressure and beating mechanism for uniting material comprising two rollers between which the material passes, one of said rollers being held with pressure in constant contact with the material, and mechanism for imparting pulsations to said roller without moving it out of contact with the material, and means for turning the other of said rollers to effect a feeding of the material. 125
